UNITED STATES PATENT OFFICE.

GEORGE F. RAYMOND, OF JACKSON, MICHIGAN.

OIL BURNER.

1,403,565.

Specification of Letters Patent. Patented Jan. 17, 1922.

Application filed December 6, 1920. Serial No. 428,501.

To all whom it may concern:

Be it known that I, GEORGE F. RAYMOND, a citizen of the United States of America, residing at Jackson, in the county of Jackson and State of Michigan, have invented 5 certain new and useful Improvements in Oil Burners, of which the following is a specification, reference being had therein to the accompanying drawings.

10 This invention relates to oil burners. It is particularly well adapted to burn kerosene but is capable of burning any fuel oil adapted to be converted into a gas by the application of heat.

15 It is the purpose of the invention to provide a burner of the character indicated which will be of a very simple and economical construction; will be susceptible of easy and accurate control and will not be rendered inoperative by reason of carbonization.

20 A further object of the invention is to provide a burner in which the parts are so combined that any carbon deposits from the oil will be deposited adjacent a clean-out 25 opening through which they may be discharged under the influence of the burner pressure itself and without disassembly of the burner as a whole.

30 Further objects and advantages of the invention will be set forth in the detailed description which now follows:

In the accompanying drawing:

35 Figure 1 is a perspective view of a burner constructed in accordance with the invention;

Fig. 2 is a vertical sectional view there- 40 through; and

Fig. 3 is a vertical section at right angles to that of Fig. 2 through a cross coupling 45 hereinafter described.

Like numerals designate corresponding parts throughout the several figures of the drawing.

45 The fuel oil from a tank (not shown) or other source of supply passes through a pipe 5 into the interior of a retort 6. The pipe 5 is extended to a point near the front or free end of the retort where it terminates,

50 leaving a chamber 7 between its end and the extremity of the retort. A clean-out opening 8 which may be closed by any suitable closure, such as a plug 9, provides

means for discharging from the chamber 7 the carbon formed therein as the oil changes 55 from a liquid to a gas. A screen 10 spans the retort 6 and a body of non-combustible material 11 fills the space rearwardly of the screen 10. It will be observed that the fuel is caused to reverse its direction of move- 60 ment at the point where it is desired to deposit the carbon, freed therefrom. Where the flow of fuel is continuously in one direc- 65 tion the carbon deposits are scattered along the entire path of the fuel and thus the 65 average burner is caused to carbonize within a very short time and become useless. By reversing the direction of the fuel at the point where the fuel begins to change from a liquid to a gas, the deposit of the carbon 70 at that point is facilitated and the provision of a clean-out opening adjacent this point renders it possible to blow the accumulated carbon out of the opening 8, by merely removing the plug 9 or otherwise freeing said 75 outlet opening.

The rear end of the retort 6 may comprise a removable plug 12 to permit of the insertion or removal of the material 11 as desired.

80 The gas passes from the chamber 7 rearwardly through the material 11 and is fil- 85 tered and cleansed by the material 11 which may be mineral wool, asbestos, gravel or any other suitable porous and non-com- bustible matter. The gas passes from the retort 6 through a pipe 13 which leads from a point adjacent the rear end of the retort to a cross coupling 14. The coupling 14 is divided by a division wall 15 into two sepa- 90 rate ports 16 and 17. The port 16 estab- lishes communication between the lower end of the pipe 13 and one end of a ring or coil pipe 18, while the port 17 establishes com- 95 munication between the other end of the ring or coil pipe 18, and a discharge pipe 19 which leads to a nozzle 20. A control- 100 ling valve 21 of any usual and conventional form serves to control the flow of gas from the pipe 19 to the nozzle 20, and thus the flames may be "turned up" or "turned down" at will.

105 The flow of gas is as indicated by the arrows, that is the gas flows from pipe 13 into one end of the ring pipe 18 and flows through the ring pipe and enters the cou-

pling 14 again through the port 17. It passes through this port and is discharged through pipe 19 into the burner proper.

For convenience of illustration, I have 5 illustrated this burner as consisting of a pair of spaced plates 22 and 23 held in their spaced relation by bolts 24 and supporting between them a gauze or wire mesh surface 25 of flame resisting material. The lower 10 plate 22 carries a mixing tube 26 and the gas discharged from the nozzle 20 together with the air drawn through the mixing tube 26 are discharged against the under side of the plate 23 and spread outwardly in a usual 15 and known way.

It is to be understood that the invention is not limited to the particular type of burner shown. The burner proper comprising the plates 22 and 23 and the gauze 25 20 have been illustrated in the accompanying drawing merely to show the relationship of the retort and the remaining elements to a burner. An ordinary flat plate burner or an ordinary casting having slits cut there- 25 in, in a manner well known in the art, could be substituted for the particular spaced plates and gauze herein shown and described, without departure from the invention, the invention residing more particu- 30 larly in the retort and ring pipe and the association of these two with a burner than in any particular kind of a burner. It will be observed that while the ring pipe 18 is disposed within the zone of heat from the 35 burner it is not disposed directly in the path of the flame. This prevents the rapid burning out of this pipe. The particular location of this pipe with respect to the height of the burner is a matter of choice. 40 I prefer, however, to locate the ring pipe as shown. Furthermore, it is manifest that the ring pipe or coil 18 may be given more than one turn about the burner without departure from the basic principle involved. 45 From the foregoing description it will be seen that a burner constructed in accordance with the present invention comprises but a few very simple and inexpensive parts and that consequently it may be very economi- 50 cally manufactured. It will also be seen that the ready cleansing of the burner is provided for and the carrying of carbonaceous particles throughout the path of the fuel is prevented and that consequently the 55 carbonization of the burner is avoided. Furthermore by disposing the ring pipe as shown, a sufficient body of heated gas is maintained even though the burner be turned low, to provide for the ready start-

ing of the burner when more heat is again 60 desired.

It is to be understood that the invention is not limited to the precise construction set forth but that it includes within its purview whatever changes fairly come within 65 either the terms or the spirit of the appended claims.

Having described my invention, what I claim is:

1. In combination a retort consisting of 70 an elongated body, a fuel supply pipe extending longitudinally therethrough and terminating short of the front end thereof, a clean-out opening at the front end of the retort, a discharge pipe leading from the 75 retort adjacent the rear end thereof and a body of porous noncombustible material disposed within the retort about the fuel supply pipe, all of said material lying rearwardly of the front end of said fuel supply 80 pipe leaving a free space between said material and the clean-out plug.

2. A structure as recited in claim 1 in combination with a ring pipe, a burner about 85 which said ring pipe extends and over which the retort is disposed, means for establishing communication between the discharge pipe and one end of the ring pipe, means for establishing communication between the 90 other end of the ring pipe and a second discharge pipe and a nozzle to which the second discharge pipe leads.

3. In combination a burner, a gas supply nozzle associated therewith, a pipe leading 95 to said gas supply nozzle, a coupling through which said pipe leads, a ring pipe extending around said burner and connected to said coupling, said coupling establishing communication between one end of said ring pipe and the first named pipe, a retort comprising an elongated body overlying the 100 burner and having a discharge pipe leading therefrom adjacent its rear end and communicating with said coupling, said coupling establishing communication between said last named pipe and the other end of the ring pipe, a fuel pipe extending longitudinally through the retort and terminating adjacent the front end thereof, a body of porous non-combustible material in the 110 retort rearwardly of the front end of the fuel supply pipe, a clean-out opening formed in the front end of the retort and a closure for said opening.

In testimony whereof I hereunto affix my 115 signature.

GEORGE F. RAYMOND.
